CLAIM

The ornamental design for a front high beam light for an automotive vehicle, as shown and described.

DESCRIPTION

FIG. 1 is a perspective view of a front high beam light for an automotive vehicle, of the new design;

FIG. 2 is an enlarged perspective view thereof;

FIG. 3 is a side view thereof;

FIG. 4 is a top view thereof;

FIG. 5 is a bottom view thereof;

FIG. 6 is a front view thereof;

FIG. 7 is a side view thereof, opposite that of FIG. 3;

FIG. 8 is a back view thereof; and,

FIG. 9 is an enlarged top view, taken within area 9 from FIG. 2.

The broken lines seen in FIGS. 1-9 and the dotted lines in FIGS. 5, 7 and 8 depict portions of the drawing that form no part of the claimed design.

1 Claim, 8 Drawing Sheets
